CLAIM

The ornamental design for a wristwatch and strap, as shown and described.

DESCRIPTION

FIG. 1 is a front elevational view of a wristwatch and strap showing my new design;

FIG. 2 is a rear elevational view;

FIG. 3 is a right side elevational view, the left side elevational view being a mirror image;

FIG. 4 is a front elevational view of a second embodiment of FIGS. 1-3 of my new design;

FIG. 5 is a rear elevational view;

FIG. 6 is a right side elevational view, the left side elevational view being a mirror image;

FIG. 7 is a front elevational view of a third embodiment of FIGS. 1-3 of my new design;

FIG. 8 is a rear elevational view;

FIG. 9 is a right side elevational view, the left side elevational view being a mirror image;

FIG. 10 is a front elevational view of a fourth embodiment of FIG. 1-3 of my new design;

FIG. 11 is a rear elevational view; and

FIG. 12 is a right side elevational view thereof, the left side elevational view.

FIG. 1

FIG. 2

FIG. 3

FIG. 4

FIG. 5

FIG. 6

FIG. 7

FIG. 8

FIG. 9

FIG. 10

FIG. 11

FIG. 12

UNITED STATES PATENT AND TRADEMARK OFFICE
CERTIFICATE OF CORRECTION

PATENT NO. : Des 320,566
DATED : October 8, 1991
INVENTOR(S) : Ericson

It is certified that error appears in the above-identified patent and that said Letters Patent is hereby corrected as shown below:

On the title page, change the title of the invention from "[54] WRISTWATCH AND STRAP" to -- [54] DOUBLE WATCH -- .

On the title page, change the name of the Assistant Examiner from "Antonic D. Davis" to -- Antoine D. Davis -- .

On the title page, change the claim from "The ornamental design for a wristwatch and strap, as shown and described" to -- The ornamental design for a double watch as shown and described. --

On the title page, change from "Fig. 1 is a front elevational view of a wristwatch and strap showing my new design." to -- Fig. 1 is a front elevational view of a double watch showing my new design. --

Signed and Sealed this
Second Day of March, 1993
